[57] CLAIM

The ornamental design for a conveyor paddle, as shown and described.

DESCRIPTION

FIG. 1 is a frontal view of a chain-driven paddle used to move particulate material along the trough of a conveyor; FIG. 2 is a right side view of the paddle of FIG. 1, the left side view being a mirror image thereof;

FIG. 3 is a top edge view taken from above the paddle of FIG. 1;

FIG. 4 is a bottom view of the paddle of FIG. 1; and, FIG. 5 is a view looking from the opposite side of FIG. 1.
